UNITED STATES PATENT OFFICE.

WALTER D. SCHMITS AND EMIL MUUSS, OF NEW YORK, N. Y., ASSIGNEES TO JACOB AND JOSEF KOHN, INCORPORATED, OF VIENNA, AUSTRIA-HUNGARY.

CHAIR.

1,005,330.

Specification of Letters Patent.

Patented Oct. 10, 1911.

Application filed July 6, 1911. Serial No. 637,116.

To all whom it may concern:

Be it known that we, WALTER D. SCHMITS and EMIL MUUSS, citizens of the United States and Germany, respectively, and both 5 residents of New York city, county and State of New York, have jointly invented a new and Improved Chair, of which the following is a specification.

This invention relates to a chair having 10 a permanent cane seat and a removable auxiliary seat adapted to be superimposed on the cane seat and to be detachably secured to the seat frame. The construction is such that the auxiliary seat may be readily applied 15 or removed that it is not liable to scratch or otherwise injure the seat frame or cane bottom and that any unsightly attaching means are obviated.

In the accompanying drawing: Figure 1 20 is a perspective view of a chair embodying our invention; Fig. 2 a plan with the auxiliary seat partly broken away; Fig. 3 a section through the auxiliary seat attaching means, and Fig. 4 a plan of part of the seat 25 frame and part of the cane seat.

A chair 10 of suitable pattern is provided with a permanent seat frame 11 which is overlapped along its inner side by a cane bottom 12 which is secured to frame 10 30 at 13 as usual. At preferably opposite points there are formed in that section of frame 11 which is overlapped by cane bottom 12 a pair of upright apertures 14 such apertures being alined with corresponding 35 apertures or meshes 15 of cane bottom 12. With the construction described, apertures 14 are readily accessible from the top and are nevertheless so surrounded by the strands of the cane, that they are practically 40 invisible and will not in any way impair the looks of the chair. Upon seat frame 11 is adapted to be placed an auxiliary seat A which when applied covers up the cane bottom and projects partly or entirely over seat 45 frame 11. The auxiliary seat is shown to be of the upholstered or cushioned kind, it being provided with a rigid bottom plate 16 that overlies the cane bottom and extends over the meshes 15 thereof and also over the aper- 50 tures 14 of frame 11.

The batting 17 of seat A is covered by a plurality of textile layers 18, which are tucked under the edges of plate 16 and thus form a pad intermediate the auxiliary seat and the seat frame 11, so that the latter is 55 not liable to be scratched. A lining 19 nailed to plate 16 covers up and protects the edges of this pad as shown.

Depending from each side of plate 16 is a threaded bolt 20 adapted to be projected 60 through the corresponding apertures 15, 14 of seat 12 and frame 11. In order to reliably attach this bolt to plate 16 the latter is provided with a squared opening bushed as at 21 and adapted to snugly accommodate 65 an upper squared bolt section 22. The bolt head 23 is covered up by a cap 24 secured to plate 16, so that by the means described, the bolt is held against rotation and is also prevented from piercing batting 17 and covering 70 18. The lower threaded end of the bolt is adapted to receive a winged nut 25 adapted to be tightened up against the lower side of seat frame 11.

If the chair is to be used with a cane seat, 75 nuts 25 are unscrewed and the auxiliary seat A together with its depending bolts 20 is lifted off frame 11. If the auxiliary seat is to be used, bolts 20 are passed through the apertures 15 of the cane seat and apertures 80 14 of frame 11, so as to project with their threaded ends below such frame. The nuts 25 being now applied and tightened up, the auxiliary seat will be securely attached to the chair in such a manner that the cane 85 bottom is entirely covered up and concealed.

It will be seen that by the construction described, the auxiliary seat may be readily applied and removed, that there are no objectionably obtrusive fastening means, that 90 the chair is not weakened for the reception of the auxiliary seat and that when the latter is applied there is nothing whatever to indicate the presence of the fixed cane seat therebeneath.

Though the auxiliary seat is shown to be of the upholstered type, a differently constructed seat may obviously be used.

We claim:

A chair provided with a permanent seat 100

frame having a pair of apertures, a meshed cane bottom secured to the frame and having openings alined with said apertures, a removable auxiliary seat adapted to be supported upon the fixed seat frame, and fastening means adapted to pass through said apertures and openings and to connect the

auxiliary seat with the permanent seat frame.

WALTER D. SCHMITS.
EMIL MUUSS.
